SPIKE FOR A SHOE

Nobuyuki Mori, Takasago, Japan, assignor to
Onitsuka Co., Ltd., Kobe, Japan

Filed Aug. 20, 1973, Ser. No. 389,950

Term of patent 14 years

Int. Cl. D2—04

U.S. Cl. D2—314

Fig. 1

Fig. 3

Fig. 4

Fig. 2

Fig. 6

Fig. 5

Fig. 8

Fig. 7

Fig. 9

FIG. 1 is a front elevational view of a spike for a shoe showing my new design;

FIG. 2 is a side elevational view thereof;

FIG. 3 is a top plan view;

FIG. 4 is a bottom plan view;

FIG. 5 is a top plan view of the spike with the anchoring flange removed;

FIG. 6 is a front elevation view thereof;

FIG. 7 is a side elevational view;

FIG. 8 is a bottom plan view; and

FIG. 9 is a cross sectional view of the spike as shown in FIG. 1.

I claim:

The ornamental design for a spike for a shoe, as shown.
